By appointment, Sec. Chittenden & Miles,
Attorneys.

UNITED STATES PATENT OFFICE.

JOHN LE MAY, OF AURORA, ILLINOIS, ASSIGNOR TO AURORA METAL COMPANY, OF AURORA, ILLINOIS, A CORPORATION OF ILLINOIS.

CONTAINER.

Application filed February 23, 1923. Serial No. 620,787.

To all whom it may concern:

Be it known that I, JOHN LE MAY, a citizen of the United States, residing at Aurora, in the county of Kane and State of Illinois, have invented a new and useful Improvement in Containers, of which the following is a specification.

This invention relates to improvement in containers and more especially to a container or box adapted for holding packing segments such as are used for packing the valve stems and piston rods of locomotives.

The segments of this kind of packing are designed to fit together to form a unit packing. When the segments are in place on the valve stem or piston rod in the retainer cage, they cannot become separated or displaced. In shipping the segments, however, in containers it is necessary to provide some means to keep them in proper position with respect to each other. If this is not done, the segments will become disordered in the container which is likely to bring some of the sharp edges into contact with the smooth surfaces with consequent injury to the segments. It is obvious, also, that the packing segments present a much neater and more attractive appearance when properly arranged in the containers, than if disordered. My improved container is also so designed that the sharp square edges of the packing segments may be accommodated in the container without danger of injury to the container or the segments. My container is so designed that such accommodation for these sharp edges permits the segments of the packing to fit snugly against the bottoms and sides of the box, thus preventing any rattling or movement of the pieces. Other features and advantages of my invention will appear more fully as I proceed with my specification.

In that form of device embodying the features of my invention shown in the accompanying drawings, Fig. 1 is a top plan view of the improved container, with the cover removed showing the packing segments in place, Fig. 2 is a top plan view of the cover, Fig. 3 is a top plan view of the box, and Fig. 4 is a vertical sectional view taken as indicated by the line 4 of Fig. 1, showing the box with the segments resting on top of another similar empty box.

As shown in the drawings, the container comprises a substantial cylindrical metal box

including the box proper 10, and the cover 11. The cover 11 is adapted to form a telescopic fit over the box 10, as shown in Fig. 4. The metallic packing segments are shown in Fig. 1, in place in the box as indicated by 13, 13. These segments when in proper position as shown in Fig. 1, form a ring, which lies against the circular side of the box 10. In order to hold these segments in proper position in the form of this ring, the bottom of the box 10 is provided with a centrally arranged circular raised or offset part 14, the diameter of which is equal to the internal diameter of the ring formed by the packing segments. This circular raised part 14, further acts as a form or core to hold the segments 13 in proper place. The cover 11 is provided with a similar centrally arranged circular offset part 15 which bears against the inner edges of the packing segments 13 at their upper ends, to assist in retaining them in proper position in the box.

The bottom of the box, at its outer edge is also provided with a circular depression or groove 17. This groove is formed for the purpose of accommodating the sharp square edges 18 of the segments. It is practically impossible to form a box, especially out of sheet metal with a perfectly square internal corner. Since the corners 18 of the packing segments are perfectly square and sharp they would cut into the corner of the box if it were rounded. Such cutting would injure the box and also the edges of the packing segments. The provision of the groove 17, however, affords accommodation for the sharp corners 18 and permits the outer curved surface of the segments 13 to fit snugly against the inner curved surface of the box 10. This snug fit with the raised part 14 on the bottom of the box and the depression 15 on the cover, serves to hold the packing segments snugly in position and effectively prevents displacement or movement of the parts.

The cover 11, at its upper outer edge is provided with a circular recess 20 adapted to accommodate the projection formed by the groove 17, so that the boxes will nest together as shown in Figure 4.

While I have shown and described certain embodiments of my invention, it is to be understood that it is capable of various modifications. Changes, therefore, in the construction and arrangement may be made

without departing from the spirit and scope of the invention as disclosed in the appended claims, in which it is my intention to claim all novelty inherent in my invention as broadly as possible in view of the prior art.

What I claim as new and desire to secure by Letters Patent, is:

1. A container adapted to hold packing segments, the container having an upstanding wall with which the segments are adapted to contact, and a lateral wall having a groove at the base of said upstanding wall adapted to accommodate the square edges of the packing segments when in place in the container.
2. A container adapted to hold packing segments, the container having an upstanding wall with which the segments are adapted to contact, a bottom wall having a depression in the outer edge adapted to accommodate the square edges of the packing segments when in place in the container, and said bottom wall having a substantially central raised portion adapted to engage the inner surfaces of the segments.
3. A container adapted to hold packing segments, the container having an upstanding wall with which the segments are adapted to contact, a bottom wall having a depression in the outer edge adapted to accommo-

date the square edges of the packing segments when in place in the container, and said bottom wall having a substantially central raised portion adapted to engage the inner surfaces of the segments, and a cover having a depressed portion in line with said raised portion and adapted to engage the upper inner surfaces of said packing segments.

4. A container adapted to hold packing segments having an upstanding side wall with which the segments are adapted to contact, the container being in engagement with its marginal wall, the container being provided with a circular groove or depression in the outer edge of the bottom of the container, adapted to accommodate the square edges of the packing segments when in place in the container and having a cover with a circular depression at the upper outer edge adapted to accommodate the flange or projection in the box formed by the groove, the projection on the bottom of one box adapted to interfit with the depression in the cover of another box in order to permit the boxes to nest together.

In witness whereof I have hereunto set my hand and seal this 19 day of February 1923.

JOHN LE MAY. [L. S.]
